UNITED STATES PATENT OFFICE.

ALEXANDRE M. GREAN, OF NEW YORK, N. Y.

BELTING.

1,280,716.

Specification of Letters Patent. Patented Oct. 8, 1918.

Application filed October 6, 1916. Serial No. 124,095.

To all whom it may concern:

Be it known that I, ALEXANDRE M. GREAN, a citizen of the United States, residing at New York, in the county of New York and State of New York, have invented certain new and useful Improvements in Belting, of which the following is a specification.

The present invention relates to belting 10 of the general character and for the purposes of that disclosed in my patent, No. 1,183,869, May 23, 1916.

The object is to provide a strong, flexible, and at the same time, relatively inexpensive article that may be manufactured 15 in substantially any length desired, and from which portions or sections may be cut for individual use.

In the accompanying drawings, 20 Figure 1 is a view in elevation of one side of a portion of a length of belting constructed in accordance with the present invention.

Fig. 2 is a similar view of the opposite 25 side.

Fig. 3 is a cross sectional view, and

Fig. 4 is a cross sectional view somewhat diagrammatic in its character, showing the elements separated to more clearly illustrate the construction and relation thereof. 30

Fig. 5 is a detail view of a portion of the finished material when laid out straight.

Similar reference numerals designate corresponding parts in all the figures of the 35 drawings.

In the embodiment disclosed, a casing strip 5 of woven flexible material is employed, the longitudinal marginal portions 6 of said strip being doubled inwardly toward each other, this strip thus producing a casing, the edges 7 of the strip preferably meeting centrally and forming a longitudinal joint.

Within the casing thus produced, is 45 located a reinforcing strip 8 also of woven material, which is preferably coarser and stiffer, a suitable filling being employed in said strip 8 to produce the desired stiffness.

Extending longitudinally along one side 50 of the casing strip and bridging the joint between the edges 7, is a tape 9, also of woven material, this tape being secured in

place by suitable means, as for example, a zigzag line of stitching 10, which passes 55 through the tape 9, the margin 6, the central portion of the reinforcing strip 8 and the opposite wall or body of the casing strip 5.

The belting thus produced is shaped to 60 have permanent transverse curvature, and the margins are made longer than the central portion. In its construction the preferable method is to associate and secure the various parts together, and afterward 65 produce the said curvature by moistening the belting and shaping the same between heated dies. One of these dies is a round block having a transversely curved surface, and the cooperating die has a reversely 70 shaped mating surface. The material when pressed between said dies has its side margins stretched or made longer than its intermediate part, thereby producing the transverse curvature. It will be understood that 75 other methods may be employed.

From the foregoing, it is thought that the construction, operation and many advantages of the herein described invention will be apparent to those skilled in the art, 80 without further description, and it will be understood that various changes in the size, shape, proportion, and minor details of construction may be resorted to without departing from the spirit or sacrificing any of 85 the advantages of the invention.

Having thus fully described my invention, what I claim as new, and desire to secure by Letters Patent, is:—

1. As an article of manufacture, a length 90 of belting, comprising a casing strip of flexible material having its side margins turned inwardly toward each other, a reinforcing strip located within the casing thus formed, and a line of zig-zag stitching passing 95 through the edges of the strip and through the intermediate portions of the reinforcing strip and bridging the joint formed by the adjacent edges of the casing strip, the longitudinal margins of the belting being 100 longer than the intermediate stitched portion to provide a transverse curvature.

2. As an article of manufacture, a length 105 of belting comprising a casing strip of flexible material having its side margins doubled inwardly toward each other, a reinforcing

strip located within the casing thus formed, and means securing the inturned longitudinal edges of the casing strip and the intermediate portion of the reinforcing strip together, said length of belting being shaped to have a permanent transverse curvature and having its longitudinal margins longer than its intermediate portion

and longer than the intermediate portion of the reinforcing strip. 16

In testimony whereof, I affix my signature in the presence of two witnesses.

ALEXANDRE M. GREAN.
